UNITED STATES PATENT OFFICE.

HENRY J. KIMMAN, OF CHICAGO, ILLINOIS, ASSIGNOR TO THE CHICAGO PNEUMATIC TOOL COMPANY, OF TRENTON, NEW JERSEY, A CORPORATION OF NEW JERSEY.

PNEUMATIC HAMMER.

SPECIFICATION forming part of Letters Patent No. 707,515, dated August 19, 1902.

Application filed June 24, 1901. Renewed July 19, 1902. Serial No. 116,243. (No model.)

To all whom it may concern:

Be it known that I, HENRY J. KIMMAN, a citizen of the United States, residing at Chicago, in the county of Cook and State of Illinois, have invented certain new and useful Improvements in Pneumatic Hammers, of which the following is a specification.

This invention relates to that class of pneumatic hammers in which there is a fluid-pressure cylinder provided with a reciprocating hammer operating in a percussion manner—that is, a large number of strokes per minute; and the invention relates particularly to the construction and arrangement of the controlling-valve mechanism, which admits and cuts off fluid to each end of the cylinder to operate the piston-hammer, all of which will more fully hereinafter appear.

The principal object of the invention is to provide a simple, economical, and efficient pneumatic hammer.

A further object of the invention is to provide a pneumatic hammer with simple, economical, and efficient controlling-valve mechanism for admitting and cutting off the motive fluid to each end of the cylinder.

Further objects of the invention will appear from an examination of the drawings and the following description and claims.

The invention consists principally in a pneumatic hammer in which there is combined a cylinder provided with a reciprocating piston-hammer, a handle-base provided with a cylindrical projection extending into the rear end of the cylinder to close the same and provide an annular valve-chamber in connection therewith, and a tubular controlling-valve reciprocatingly mounted in such valve-chamber to govern the admission of the motive fluid to the cylinder.

The invention consists, further and finally, in the features, combinations, and details of construction hereinafter described and claimed.

In the accompanying drawings, Figure 1 is a sectional elevation taken through the hammer at or near its longitudinal center, as indicated by line 4 of Fig. 7, showing the piston-hammer and controlling-valve in one po-

sition; Fig. 2, a cross-sectional view taken on line 2 of Fig. 1 looking in the direction of the arrow; Fig. 3, a detail view of the tubular controlling-valve; Fig. 4, a longitudinal sectional view of the cylinder with other parts detached, taken on line 4 of Fig. 7 looking in the direction of the arrow; Fig. 5, a similar view taken on line 5 of Fig. 6; Fig. 6, a cross-sectional view taken on line 6 of Figs. 4, 5, 8, and 9; Fig. 7, a cross-sectional view taken on line 7 of Figs. 4, 5, 8, and 9; Fig. 8, a longitudinal sectional view of the cylinder with other parts removed, taken on line 8 of Fig. 11; Fig. 9, a similar view taken on line 9 of Fig. 10; Fig. 10, a cross-sectional view taken on lines 10 of Figs. 4, 5, 8, and 9; Fig. 11, a cross-sectional view taken on lines 11 of Figs. 4, 5, 8, and 9; Fig. 12, a cross-sectional view taken on lines 12 of Figs. 4, 5, 8, and 9. Figs. 13, 14, 15, and 16 are cross-sectional views taken on lines 13, 14, 15, and 16, respectively, of Figs. 4, 5, 8, and 9; and Fig. 17, a longitudinal sectional detail of the cylinder and detached mechanisms, taken on the same line as Fig. 1, showing the controlling-valve and piston-hammer in different positions from that shown in Fig. 1.

In constructing a pneumatic hammer in accordance with these improvements I make a cylinder portion *a* of the desired length and diameter and provide it with a long cylindrical operating-chamber *b*, also of the desired length and diameter. One end of this cylinder is provided with a bushing *c*, into which the shank *d* of the desired tool is fitted and which closes such end of the chamber. To transform the energy of the motive fluid into work done, a piston-hammer *d* is provided and reciprocatingly mounted in the operating-chamber of the cylinder, so that as the motive fluid enters at one end—the rear—of the cylinder the hammer is driven forward to contact the tool-shank and accomplish the necessary work, while the pressure and expansion of motive fluid in the front end of the cylinder drives the piston-hammer back again to its initial position.

In order to provide for the proper supply

of motive fluid to each end of the cylinder to operate the piston-hammer, a handle portion *f* is provided, the base of which has a tubular projection *g*, entering the rear end 5 of the cylinder to close such end of its operating-chamber. The rear end of the cylinder is formed for a short distance to a diameter slightly larger than that of the operating-chamber, so that when the tubular projection 10 of the handle-base is in position it forms an annular valve-chamber *h* between such tubular projection and the walls of the cylinder. In this annular valve-chamber is mounted a tubular or shell valve *i*, the body 15 portion of which is of a diameter smaller than the head portion, so that it forms, as it were, a differential valve, the inner side of which—that containing the smallest area—is constantly acted upon by fluid-pressure, 20 while the other or outer end—that containing a larger superficial area—is acted on intermittently by the fluid-pressure to reciprocate such valve, as will be hereinafter more fully described.

25 Describing the passages for the introduction and exhaust of motive fluid for the purpose of operating the piston-hammer, the handle is provided with a main supply-channel *j*, adapted to be opened and closed by a 30 throttle-valve, the operating-lever *k* of which is only shown. This main supply-channel connects with the axial opening in the tubular projection of the handle-base, which axial opening practically forms a continuation 35 thereof. Arranged transversely in the axial opening of the tubular projection is a partition *l* and a number of by-passes *m*, so that as motive fluid enters from the main supply-channel it enters these by-passes around the 40 partition and into the operating-chamber of the cylinder between the partition and the head of the piston-hammer to move such hammer forward. When the hammer has reached its forward limit of motion, as shown 45 in Fig. 17, motive fluid passes constantly through perforations *n* in the tubular projection, thence through a plurality of perforations *o* in the controlling-valve through passages *p* in the cylinder, (see Figs. 4 and 50 17,) from which it passes forward and enters the operating-chamber of the cylinder opposite an annular groove *q*, formed in the hammer-head. From this annular groove it passes into passages *r*, (see Fig. 8,) thence back to 55 the rear of the valve-chamber and between the head of the valve and the handle-base, where, acting on the largest superficial area of the valve, it moves the same forward into the position shown in Fig. 17. This movement of the controlling-valve closes the by-pass *m* and cuts off the motive fluid from entering at the rear of the piston-hammer. At the same time the motive fluid between the piston-hammer and the partition in the tubular projection of the hammer passes out 60 through the exhaust-passage *s*, thence backwardly through such passage into an annular

groove *t* in the cylinder, thence over into a second annular groove *u* out through the perforations *v* into an annular exhaust-chamber 70 *w*, formed between the hammer-handle and the outside walls of the cylinder, from whence it is discharged through the exhaust-perforations *x* into the open air, thus exhausting the excess of atmospheric pressure from the 75 back of the piston-hammer. The hammer is now in position to be moved backward, and in order to accomplish this result the motive fluid passes from the annular chamber *q* formed in the hammer-head, through the 80 channels *y* to the front of the cylinder between the piston-hammer and the shank of the tool, and operates to move the piston-hammer forward. During the backward movement of the piston-hammer it passes the exhaust-opening *s*, cuts off the escape, and compresses the remaining air between the partition in the tubular projection and the hammer-head to absorb or take up the recoil of 85 the hammer. During the same movement of the piston-hammer the exhaust-openings 90 at the front are uncovered, so that the excess of pressure in front of the piston-hammer and between it and the tool-shank may be exhausted into the open air. At the same time 95 the motive fluid between the differential valve and the handle-base passes forwardly through the passage *r* and the continuation 100 thereof, where it enters the forward part of the operating-chamber and passes out 105 through the exhaust-openings *s*, thus permitting the constant supply of motive fluid that passes through the perforations *n* in the tubular projection and *o* in the controlling-valve to act upon the shoulder 22, by which 110 it is in a measure confined against a shoulder formed by the passage *p* to move such controlling-valve backward and again open the by-passes *m*. This permits a supply of motive fluid to again enter the operating-chamber of the cylinder between the hammer-head and the partition in the tubular projection to again move such piston-hammer forward. The shoulder 22 on the valve at the same 115 time cuts off communication between the annular channels *t* and *u* and acts to close the exhaust from the rear end of the operating-chamber.

An examination of the drawings will show 120 that when the controlling-valve is moved forward into the position shown in Fig. 17 it is desirable to have some means by which any air between the front end of such controlling-valve and the shoulder 24, formed by the cylinder-walls, may escape. To accomplish 125 this result, supplementary exhaust-openings 23 are provided adjacent to the shoulder which forms the inner end wall of the annular valve-chamber, so that any air confined 130 between such shoulder and the front end of the tubular valve will pass out through such opening. Emergency exhaust-passages 25 are also provided in the cylinder-walls, which connect with the extreme forward end of the

operating-chamber, so that when the piston-hammer during its forward motion, as shown in Fig. 17, passes the forward exhaust-openings, any air confined in the front end of the operating-chamber will pass rearwardly through these emergency exhaust-passages 25 into the forward end of the annular valve-chamber and out through the openings 23.

To secure the handle to the cylinder, the 10 rear end of the cylinder is screw-threaded at 26 and the handle portion provided with an internal screw-threaded bore adapted to engage the same. The handle is also provided with two pairs of clamping-lugs 27, having 15 bolts 28 extending therefrom to clamp the same together, as shown in Fig. 2, and act to lock all the parts in the desired assembled position.

I claim—

1. In a tool of the class described, the combination of a cylinder provided with a reciprocating piston-hammer, a handle-base provided with a cylindrical projection extending into the rear end of the cylinder to close the same and provide an annular valve-chamber between it and the cylinder, and a tubular controlling-valve reciprocatingly mounted in such valve-chamber to govern the admission of the motive fluid to the cylinder, substantially as described.

2. In a tool of the class described, the combination of a cylinder provided with a reciprocating piston-hammer, a handle-base provided with a tubular projection extending into the rear end of the cylinder to close the same and provide an annular valve-chamber between it and the cylinder, and a tubular controlling-valve reciprocatingly mounted on such projection to govern the admission of motive fluid, substantially as described.

3. In a tool of the class described, the combination of a cylinder provided with a reciprocating piston-hammer, a handle-base provided with a tubular projection extending into the rear end of the cylinder to close the same forming a continuation of the supply-channel and providing an annular chamber between it and the cylinder, a partition in such tubular projection providing a by-pass 50 for admitting the motive fluid to the cylinder, and a tubular controlling-valve surrounding such projection and reciprocatingly mounted in the annular valve-chamber to admit the motive fluid to the cylinder, substantially as described.

4. In a tool of the class described, the combination of a cylinder provided with a reciprocating piston-hammer, a handle provided with an integral tubular projection extending into the rear end of the cylinder to close the same forming a continuation of the supply-channel and provide an annular valve-chamber between it and the cylinder and provided with perforations communicating with the 65 continuous opening to furnish motive fluid for the front end of the cylinder, a transverse partition in such tubular projection forming

in connection therewith a by-pass through which the motive fluid passes to the rear end of the cylinder, and a tubular controlling-valve surrounding such projection and reciprocatingly mounted in the valve-chamber to govern the admission of the motive fluid to the rear chamber of the cylinder, substantially as described.

5. In a tool of the class described, the combination of a cylinder provided with a reciprocating hammer, a handle-base provided with a tubular projection extending into the rear end of the cylinder to close the same and provide in connection therewith an annular valve-chamber, a tubular differential controlling-valve slidably mounted in the annular valve-chamber to govern the admission of the motive fluid to the cylinder, means for admitting a constant supply of motive fluid to the smaller area of the tubular differential controlling-valve, and means arranged to be operated by the movements of the piston-hammer to intermittently admit motive fluid to the larger superficial area of the differential valve to reciprocate the same, substantially as described.

6. In a tool of the class described, the combination of a cylinder provided with a reciprocating piston-hammer, a handle-base provided with a tubular projection extending into the rear end of the cylinder to close the same and form the connection with an annular valve-chamber, a shouldered tubular differential valve in such valve-chamber, a main supply-passage formed in the hammer-handle and extending into the axial tubular opening of the projection, by-passes in such tubular projection, a transverse partition arranged in such tubular projection to assist in forming such by-passes and admit motive fluid to the rear of the piston-hammer, constant-supply passages *n* in the tubular projections, constant-supply passages *o* in the tubular valve to furnish a constant supply of motive fluid to the smaller superficial area of the shoulder, a passage *r* in the walls of the cylinder connecting the operating-chamber with the valve-chamber to the rear of the face of the valve and arranged to be opened and closed by the movements of the piston-hammer to furnish an intermittent supply of motive fluid to the larger area of the differential valve and reciprocate the same, substantially as described.

7. In a tool of the class described, the combination of a cylinder provided with a reciprocating piston-hammer, a handle-base provided with a tubular projection extending into the rear end of the cylinder to close the same and form in connection therewith an annular valve-chamber, a tubular differential valve slidably mounted in such valve-chamber, means for furnishing a constant supply of motive fluid to the smaller area of the differential valve, means arranged to be operated by the movements of the piston-hammer to furnish an intermittent supply of motive

fluid to the larger area of the differential valve and reciprocate the same, an annular exhaust-channel *u* connecting with the open air, a second exhaust-channel *t* connected with passages through the cylinder with the rear end of the operating-chamber and arranged to be opened and closed by the movements of the reciprocating controlling-valve, substantially as described.

10 8. In a tool of the class described, the combination of a cylinder provided with a reciprocating hammer, a handle-base provided with a tubular projection extending into the rear end of the cylinder to close the same and form an annular valve-chamber in connection therewith, a tubular differential valve slidingly mounted in such valve-chamber, means furnishing a constant supply of motive fluid to operate such differential valve in one direction, means for furnishing an intermittent supply of motive fluid to the larger superficial area thereof to move it in the opposite direction, an exhaust-passage in the rear end of the cylinder arranged to be opened and closed by the movements of the differential valve, a supplementary valve-exhaust opening connected with the front end of the an-

nular valve to release any air confined therein, and an emergency exhaust-passage in the walls of the cylinder connected with the front 30 end of the operating-chamber and the exhaust-openings in the annular chamber to exhaust any air in the front end of such operating-chamber, substantially as described.

9. In a tool of the class described, the combination of a cylinder provided with a reciprocating hammer and a rear outer threaded portion, a handle-base provided with a central tubular projection extending into the rear end of the cylinder to close the same 40 and provide an annular chamber between it and the walls of the cylinder, an outer annular tubular projection having an internal threaded bore engaging with the threads on the rear end of the cylinder, and bolt mechanism for locking the threaded tube of the handle-base in engagement with the threaded surface of the cylinder, substantially as described.
